UNITED STATES PATENT OFFICE.

MORRIS DAVISON AND ERNEST KANDERSON, OF PHILADELPHIA, PENNSYLVANIA.

DESIGN FOR A CONDIMENT-HOLDER.

46,986.

Specification for Design.

Patented Feb. 23, 1915.

Application filed September 5, 1914. Serial No. 860,464. Term of patent 7 years.

To all whom it may concern:

Be it known that we, MORRIS DAVISON and ERNEST KANDERSON, citizens of the United States, residing at Philadelphia, in the county of Philadelphia and State of Pennsylvania, have invented a new, original, and ornamental Design for Condiment Holders, of which the following is a specification, reference being had to the accompanying drawing, forming a part thereof.

The figure is a side elevation of a condiment holder showing our new design.

We claim:

The ornamental design for a condiment holder, as shown.

MORRIS DAVISON.
ERNEST KANDERSON.

Witnesses:

PHILIP DAVISON,
JACOB SACKS.
